(57) **CLAIM**

The ornamental design for a hockey stick case, as shown and described.

DESCRIPTION

FIG. 1 is a front elevation view of a hockey stick case showing my new design;

FIG. 2 is a right side elevation view thereof;

FIG. 3 is a bottom plan view thereof;

FIG. 4 is a top plan view thereof;

FIG. 5 is a rear elevation view thereof;

FIG. 6 is a left side elevation view thereof; and,

FIG. 7 is a elevation view thereof in the open position, wherein the broken line showings of the sticks and pucks are for illustrative purposes and form no part of the claimed design.
